Inventor
Thomas W. Cappon
By his Attorney *H. Mackay*

UNITED STATES PATENT OFFICE.

THOMAS W. CAPON, OF BROOKLYN, NEW YORK.

INK ERADICATOR.

Application filed March 8, 1924. Serial No. 697,750.

This invention relates to ink erasers, and more particularly to fluid ink erasers.

The invention has for its objects, among others to provide a device that will both contain and dispense an erasing fluid; to provide such a device that it may be readily held between the thumb and fingers; and to provide means of this character capable of use on the end of a fountain pen.

10 Several embodiments of the invention are shown in the drawings, in which

Figure 1 is a view showing the eraser applied to the cap of a fountain pen, parts being in section, the glass pencil being movable into and out of the container.

Figure 2 is a cross sectional view on the line 2—2 of Figure 1.

Figure 3 is a view similar to Figure 1, showing a modification in which a capillary aperture runs through the glass pencil, and

Figure 4 is a cross sectional view on the line 4—4 of Figure 3.

Referring to the drawings for a detailed description, there is shown a cylindrical shell 1, which is preferably the cap of a fountain pen. In place of the customary integral covering there is a detachable cap 2, of larger dimensions than the shell 1. Mounted within shell 1 is a glass container 3, sealed at one end by a rubber stopper 4, which supports at its center a glass collet 5 which has a cylindrical aperture therethrough. Any suitable container having an operating aperture for discharge of the fluid is within the invention. Mounted in the collet 5 is the glass pencil 6 provided with the curved enlargement 7 for engaging the surface of the paper and to facilitate grasping the pencil with the fingers.

40 When not in use, the cap 2 is in place and the pencil 6 is pushed all the way in, so that the exterior enlargement 7 entirely closes the operating aperture. To use the apparatus, the cap is removed and the pencil 6 is first drawn all the way out, until the interior enlargement acts as a stop. During this operation, air will enter around the pencil to occupy the space formerly occupied by the pencil within the container. The 45 apparatus is then inverted and the outer en-

largement 7 is brought in contact with the ink spot or mark to be eradicated, when, by pushing gently down, the pencil is again forced into the container. The interior displacement caused by this movement causes 55 a rise in pressure within the container which forces out an appropriate quantity of fluid around the pencil and down to the enlargement in contact with the ink spot.

In the form shown in Figure 3 the glass 60 pencil fits more tightly in the collet 5. Running through the pencil 6 is a capillary tube having the aperture 9 opening into the container 3 and the aperture 8 opening into the curved surface 7 of the writing end of 65 the pencil.

In either of the forms shown the pencil is slideable freely through the operating aperture, by which is meant that the pencil may be moved in either direction into any 70 desired position where it will remain. This distinguishes the present device from prior forms in which a spring is counted upon to maintain the pencil in one normal position, and wherein action by displacement is not 75 relied upon. Furthermore devices which rely upon springs for operation soon become quite useless, because of the chemical reaction between the ink eradicating fluid and the metal of the spring, whereby the effectiveness of the fluid is impaired and the spring is corroded.

What is claimed is—

1. A fluid ink eraser, comprising in combination a container having a narrow operating aperture and a fluid applying pencil extending in front of the outer orifice of the container and freely slideable in said aperture and provided with an enlargement at its inner end adapted to limit outward movement of said pencil; said pencil being so proportioned to the container as to produce effective ejection of fluid by displacement when pressed inward.

2. A fluid ink eraser as in claim 1 wherein 95 the pencil is provided with enlargements at both ends to limit movement in both directions.

3. A fluid ink eraser as in claim 1 wherein 100 the fluid applying pencil is hollow and

has an aperture communicating with the interior of the container.

4. A fluid ink eraser comprising in combination a container having a narrow operating aperture and a slidable fluid applying pencil having an external enlargement accessible for manual operation whereby the

same may be drawn forward preliminary to operation in applying the fluid within the container.

In testimony whereof, I have hereto set my hand on this seventh day of March, 1924.

THOMAS W. CAPPON.
